UNITED STATES PATENT OFFICE

136,603

DESIGN FOR A PURSE

Nathan Sloane and Max Sloane, Brooklyn, N. Y.

Application March 3, 1943, Serial No. 109,654

Term of patent 3½ years

To all whom it may concern:

Be it known that we, Nathan Sloane and Max Sloane, citizens of the United States and residents of Brooklyn, in the county of Kings and State of New York, have invented a new, original, and ornamental Design for a Purse, of which the following is a specification, reference being had to the accompanying drawings, forming a part thereof, and of which Fig. 1 is a view in side elevation of the purse in closed position showing our new design; Fig. 2 is a view in end elevation thereof; Fig. 3 is a view in side elevation with the upper flap shown in Fig. 1 tucked inside the purse resulting in its open position; Fig. 4 is a view in end elevation of Fig. 3; Fig. 5 is a view in side elevation on a reduced scale with the mouth expanded and the flap raised; and Fig. 6 is an end elevation of Fig. 5.

The dominant features of the invention reside in a purse of the configuration disclosed having the upper and lower flaps substantially as shown.

We claim:

The ornamental design for a purse, substantially as shown and described.

NATHAN SLOANE.
